UNITED STATES PATENT OFFICE.

CLARENCE J. RICHARDS, OF TEMPLE, CALIFORNIA.

ROOF CONSTRUCTION.

Application filed October 16, 1926, Serial No. 141,918. Renewed December 3, 1928.

This invention relates to corrugated roofs.

The general object of my invention is to construct a roof wherein fibrous material is used to produce a finished roof which simulates one shingled with tile.

Another object is to construct a corrugated composition shingle roof which, while weather proof and strong is cheap to construct owing to the fact that short lengths of lumber may be used.

Other objects of my invention will be apparent from the following description taken in connection with the accompanying drawings wherein:

15 Fig. 1 is a partial view of a house roof showing my invention;

Fig. 2 is a section of a roof showing the method of construction;

20 Fig. 3 is a section taken on line 3—3 of Fig. 2;

Fig. 4 is a top plan view showing the progressive steps employed in the construction of my roof;

25 Fig. 5 is a section through one type of valley of my roof;

Fig. 6 is an enlarged section along a valley;

Fig. 7 is an enlarged cross section through a valley showing one method of constructing the same;

30 Fig. 8 is an enlarged cross section of a ridge showing one method of construction;

Fig. 9 is a section showing a modified form of roof construction, and

Fig. 10 is a top plan view of the same.

35 As shown in the accompanying drawings I employ rafters 10 on which a series of spaced forms 11 are secured. On the forms 11 I secure a decking 12 which is covered over by shingles 13.

40 As shown in Figs. 2, 3 and 4 the forms 11 extend from the center of one rafter 10 to the center of another and are provided at their ends with rabbets 14 which fit over the rafters. The bottom edge of the forms lie

45 flush with the bottom of the rafters while the top is shown as curved rising from a low point at the center of the forms to a high point at the center of the rafters and extending above the latter in a series of graceful curves to form alternate ridges and valleys.

50 Each form consisting of one complete valley with a half of a ridge at each end. The decking 12 is then laid over the forms 11 and secured thereto by nailing.

55 For economy I prefer to construct the decking 12 of short lengths of lumber 15,

each length extending from one line of forms to another as clearly shown in Fig. 4, but of course it will be understood that the length of the decking strips 15 is immaterial and 60 may be of any desired length. Over the decking 12 and secured to the strips 15 is the shingling 13. This consists of rows of composition shingles 16 which extend from the center of one rafter to the center of the next 65 or in other words from the center of one ridge to the center of the next. The shingles have their bottom edges overlapping the top edge of the preceding shingle, (see Figs. 3 and 4). Over the ridge and extending approximately one third of the distance from the center of one ridge to the center of another I lay a row of shingles 17 70 overlapping one another similar to the shingles 16.

75 The overlapping of the shingles 16 necessitates the use of a filler shingle 18 at the lower end of the roof so that the shingles 17 may be laid without bending the same.

At the eaves of the roof I provide a finish 80 strip 19 of the same configuration as the forms 11 and sufficiently high to cover the ends of the strips 15 and the rafters 10. This finish strip is preferably secured to the ends of the rafters prior to the laying of the 85 shingles. At the gable end of the roof I provide a rafter 20 of a greater depth than the rafters 11, and to the outer side thereof I secure half round forms 21 in line with the forms 11. The curve of the forms 21 corresponds to the curve of the ridge portion of the forms 11 and matches the latter at their juncture. The decking and shingling over the form 21 is the same as over the forms 11, (see Fig. 2). At the gable end of the roof 90 the eaves are finished off on the under side by securing to the under side of the protruding forms 11 a ceiling 22 preferably made of long tongued and grooved boards. Secured to the rafter 20 and the underside of the ceiling 22 I provide other false rafters 23 laid at right angles to the rafter 20, for ornamental purposes only.

100 For this type of roof it is necessary to provide a novel form of valley and in Figs. 5, 6 and 7 I have shown one form of diagonal valley involving the features of my invention, which may be used at the juncture of the two roof portions "A" and "B" of Fig. 1. The valley as shown, comprises a U-shaped form 110 consisting of side members 25 and 26 secured to a bottom member 27. The side members

25 and 26 are of such a configuration as to allow the decking 12 to join the valley without any distortion of the configuration given to it by the forms 11. This may require some 5 hand fitting and the use of a hatchet which will leave a more or less ragged surface consequently in order to be sure of a good contact of the decking with the side members 25 and 26, I use several layers of a feltlike packing 10 28 known as "Irish moss" laid with a coat of hot tar between each layer. For the purpose of weather proofing, I apply a substantial coat of tar 29 to the entire valley and for ornamental purposes I apply a coating of 15 crushed rock 30 over the hot tar. The crushed rock used will preferably be of the same color as the composition shingles making the whole roof the same color.

In the construction of a straight valley 20 there will be no elongation of the curves of the side members 25 and 26, they will merely be of the same configuration as the forms 11 and packed with the moss 28, and coated with tar and crushed rock the same as the diagonal 25 valley.

In Fig. 8 I have shown one form of ridge construction which consists in securing to each side the ridge pole 32 a series of forms 33 similar to the forms 11, and provided with 30 slots for the passage therethrough of the rafters 10. Secured to the forms 33 in the same manner as the forms 11 is the decking 12 and the shingles 13. On the top of the ridge pole 32 I provide a member 34 which 35 projects out over the shingling. Secured to the decking 12 and the chamfered edges of the member 34 is an arched crown member 35 similar in texture and color to the shingling 13. The space between the member 25 and 40 the member 34 is packed with hot tar and Irish moss.

In Fig. 9 I have shown a roof constructed similar to that previously described except that I use, instead of the short forms 11, 45 which reach only from center to center of the rafters, elongated forms 40 which span a plurality of the rafters 10 on which decking strips 15 are laid. In Figs. 9 and 10 I also show a slightly different method of applying 50 the covering. This consists of first laying and securing to the decking 15 strips of ma-

terial such as building paper 41 which extend the full length of the roof instead of only from center to center of the ridges as previously described. These strips overlap at 55 their edge 42. Over these strips 41 the shingles 17' are laid in the same manner as hereinbefore mentioned. The texture and color of the strips 41 is preferably the same as the shingles 17.

From the foregoing description it will be seen that I have invented an improved roof which is highly efficient, ornamental and may be economically manufactured.

What I claim is:

1. A roof construction comprising a plurality of substantially parallel rafters extending upwardly from the eaves, a plurality of form members arranged on said rafters and extending at substantially right angles to said rafters, said form members having a part fitted over the top and a part extending downward and parallel to the sides of said rafters, the upper surface of said form members being corrugated to form valleys and ridges, 70 decking strips arranged on the form members and transverse thereto in close parallel relation, said decking strips extending substantially parallel to said rafters, and a flexible waterproof member arranged on said decking strips.

2. A roof construction comprising a plurality of substantially parallel rafters extending upwardly from the eaves, a plurality of form members arranged on said rafters and extending at substantially right angles to said rafters, said form members being recessed to fit over the top and the sides of said rafters and the upper surface of said form members being corrugated with the valleys of the corrugations disposed between the rafters and with the ridges of the corrugations surmounting the rafters, decking strips arranged on the form members in close parallel relation, said decking strips extending substantially parallel to said rafters and a flexible non-metallic waterproof member arranged on said decking strips.

In testimony whereof, I hereunto affix my signature.

CLARENCE J. RICHARDS.
